US0D1096035S

(12) **United States Design Patent** (10) **Patent No.:** **US D1,096,035 S**
(45) **Date of Patent:** **** Sep. 30, 2025**

(54) **CAR CLEANING KIT**

(71) Applicant: **Shenzhen Guowei Zhizao Technology Co., Ltd.**, Shenzhen (CN)

(72) Inventor: **Pingguo Ming**, Shenzhen (CN)

(73) Assignee: **Shenzhen Guowei Zhizao Technology Co., Ltd.**, Shenzhen (CN)

(**) Term: **15 Years**

(21) Appl. No.: **29/922,684**

(22) Filed: **Dec. 25, 2023**

(51) **LOC (15) Cl.** **07-05**

(52) **U.S. Cl.**

USPC **D32/35**

(57) **CLAIM**

The ornamental design for a car cleaning kit, as shown and described.

DESCRIPTION

FIG. 1 is a rear, right and bottom perspective view of a car cleaning kit showing my new design;

FIG. 2 is a front, left and top perspective view thereof;

FIG. 3 is a front, left and top perspective view of the car cleaning kit of FIG. 2, shown in condition of use;

FIG. 4 is an exploded view thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

The broken lines in the figures illustrate portions of the car cleaning kit that form no part of the claimed design.

1 Claim, 10 Drawing Sheets
